(57) **CLAIM**

The ornamental design for a chisel handle, as shown and described.

DESCRIPTION

FIG. 1 is a perspective view of a chisel handle showing my new design, and including a typical chisel blade shown in broken lines and which forms no part of the present invention;

FIG. 2 is a top plan view thereof;

FIG. 3 is a left side elevational view thereof, the right side being a mirror image thereof;

FIG. 4 is a front elevational view thereof; and,

FIG. 5 is a rear elevational view thereof.
